UNITED STATES PATENT OFFICE.

JOSEPH FIDELIS DE MACEDO, OF VICTORIA, BRITISH COLUMBIA, CANADA.

FASTENING FOR ENVELOPS AND THE LIKE.

1,097,811.

Specification of Letters Patent. Patented May 26, 1914.

Application filed May 29, 1913. Serial No. 770,757.

To all whom it may concern:

Be it known that I, JOSEPH FIDELIS DE MACEDO, British subject, residing at Victoria, in the Province of British Columbia, in the Dominion of Canada, have invented a new and useful Fastening for Envelops and the like, of which the following is a specification.

The usual mode of closing an envelop is to moisten the flap of the envelop with the lips or tongue and then press it against the body of the envelop until it adheres thereto and in cases where security is desired, to seal it with sealing-wax.

The object of my invention is to produce a cheap and simple fastening by which an envelop may be securely and expeditiously closed without having recourse to the dirty practice of licking gum or to the dilatory and inconvenient use of sealing-wax.

My fastening consists of two complementary members, one of them fixed to the flap of the envelop (hereinafter called the flap-member) and the other fixed to the body of the envelop (hereinafter called the body-member) the former consisting of one piece or part A and the latter consisting of two pieces or parts B and C.

In the annexed drawing Figure 1 is a plan and Fig. 2 is a section (on the broken line X Y) of the flap-member A. Fig. 3 and Fig. 4 are a plan and section of the piece B one of the component parts of the body-member. Fig. 5 and Fig. 6 are a plan and section respectively of the fastener in its locked condition and Fig. 7 is a full sized view of the fastening as applied to an envelop.

The flap-member A (Fig. 1 and Fig. 2) is stamped out of thin sheet metal about $\frac{1}{100}$ of an inch thick (31 Birmingham W. G.) and then pressed into the shape shown in the drawing, the three wedge-shaped protuberances *d d d* being embossed and projecting sufficiently to fill the pocket into which the tongue will be inserted when the fastening is closed.

e e e are prongs which after first being bent perpendicular to the face of the metal are pressed through the flap of the envelop and clenched on the inner side, thus fastening the flap-member securely in its place. In the middle of the tongue *J* which forms the lower part of the flap-member there is stamped a triangular catch or tooth *h* shaped like the tooth of an ordinary hand-

saw, and pressed perpendicular to the face of the tongue by means of a triangular punch, two of whose sides only have a cutting edge. It will be observed from the drawing that the tongue *J* is made wide at its root *m n*.

The part B is a disk stamped out of a thin sheet of metal, preferably steel, in the center of which is a rectangular flap *f* formed by cutting three of its sides and bending it so as to project beyond the surface of the disk as shown in Fig. 4. The part B is made just the proper size to fit into the cavity of the part C as shown in Fig. 6. The said part C is stamped out of thin sheet metal and is shaped as shown in the drawing, the central part being dished and having an opening *m n* at its upper edge equal to the width of the root of tongue *J* so that when the part B is fixed into its place as shown in Fig. 6 a pocket is formed into which the tongue *J* may be inserted when the fastening is closed. The part B is fixed into the concave part of C so that the spring flap *f* projects inwardly.

At the circumference of the part C are three prongs or lugs *K K K*, which having been first bent perpendicular to the face of the metal are then pressed through the three paper flaps forming the body of the envelop and are clenched on the inner side thus fastening the body-member to the envelop and at the same time holding the part B in its place.

The flap-member and body-member are secured to the envelop in such a position that when the envelop is closed they will register properly with each other, and that when the tongue is inserted into the slot the spring flap *f* will be pressed back by the catch *h* and when it rebounds will securely lock the tongue in place, the protuberances *d* making it impossible to insert a flat instrument to pry spring flap *f* toward disk B to open the fastener. It is thus seen that it is impossible for the tongue to be withdrawn without rupturing some part of the fastening and leaving plain indication of the envelop's having been tampered with.

I claim as my invention:

A fastener for envelops, comprising a pair of interlocking members, each of which is provided with a means for attaching it to the envelop, one of the said members being attached to the closure flap, said member consisting of a sheet metal plate provided with a depending tongue, said tongue hav-

ing its sides merging to a point whereby a substantially conical member is provided having a number of wedge shaped protuberances embossed thereon near its upper end 5 and having a triangular shaped tooth punched from the plate of sheet metal near the lower end of the tongue, and standing out perpendicular to lower face thereof the other member fastened to the body of the 10 envelop consisting of a pocket formed of a dished member, and a sheet metal disk clos-

ing the same, said dished member having an opening for the insertion of the tongue on the first mentioned member, and said disk having a struck-up tongue standing at an 15 angle to the said disk for coöperation with the tooth at the lower portion of the first member.

JOSEPH FIDELIS DE MACEDO.
